(57) CLAIM

The ornamental design for an electric guitar, as shown and described.

DESCRIPTION

FIG. 1 is a front perspective view of an electric guitar showing our new design;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof; and,

FIG. 7 is a right side view thereof.

The broken lines illustrate portions of the electric guitar and form no part of the claimed design. The dash-dotted lines denote the boundary of the claim and form no part of the claimed design.

1 Claim, 7 Drawing Sheets
